UNITED STATES PATENT OFFICE

JAMES D. COLE, OF CLEVELAND HEIGHTS, OHIO, ASSIGNOR TO DOMESTIC ELECTRIC COMPANY, OF CLEVELAND, OHIO, A CORPORATION OF OHIO

EXERCISER MECHANISM

Application filed November 22, 1929. Serial No. 408,969.

The primary object of this invention is to provide a simple and effective mounting for an exerciser mechanism, such as the type employing a belt or girdle, to embrace the body or body parts of the user to impart mechanical vibrating impulses thereto. Machines of this type employ various applicator arrangements, such as hand-hold devices and belts interchangeably.

This application is a continuation, in part of my application Serial No. 315,858, filed October 29, 1928, wherein an exercising machine of the type mentioned is shown and described in detail.

A further specific object is to provide a simple device for attaching a mechanical vibrating machine to a door in such manner that the door will serve as a yielding support for the machine.

Further objects and features of the invention will become apparent from the following description relating to the accompanying drawings, wherein I have shown my preferred forms. The essential characteristics are summarized in the claims.

In the drawings, Fig. 1 is a sectional plan view of a door frame and ordinary door in open position, with the exerciser mechanism mounted thereon; Fig. 2 is a plan view showing one form of mounting, including part of the door, the stile portion only of the door being shown in horizontal cross section; Fig. 3 is a fragmentary side elevation of the exerciser mechanism and the attaching portion of the mounting, as shown in Fig. 2; Fig. 4 is a fragmentary plan view showing a modification with respect to the attaching portion of the mounting; Fig. 5 is a side elevation of the exerciser mechanism showing still another form of mounting arrangement, and Fig. 6 is a fragmentary sectional plan view taken substantially along the line 6—6 on Fig. 5.

Prior to my invention, most exerciser arrangements of the vibrating belt type were supported on special stands which were rugged enough to withstand the vibration due to the unbalanced crank effect which is inherent in these machines by reason of having to alternately pull the ends of the belt or girdle, or to actuate other exercising arrange-

ments, such as handles. A very few exerciser machines of this type were supported on ordinary tables and were provided with special securing arrangements to hold the machine in place on such tables. A common disadvantage of the latter type of machine has been that the surfaces of such tables are marred by the use of the machine due to vibratory movements of the machine in action, rapidly shifting the machine's base on the table.

My arrangement is designed to overcome these difficulties by absorbing the major portion of the practically necessary vibration by hingedly mounting the exerciser on a rugged portion of a building, the hinge axis being vertical so that the exerciser may remain at the desired height from the floor. As a practical proposition, the hinged part of the mounting preferably comprises an ordinary vertically hinged door. Thus the door serves essentially as a comparatively heavy horizontally yielding bracket which will permit sufficient give to yieldingly absorb nearly all the vibrations of the machine running idle, while not detracting from the force of the exercise when the machine is being used. Inasmuch as substantially all buildings are equipped with doors, no equivalent bracket has to be provided as a commercial proposition, a suitable clamp arrangement serving to rigidly attach the exercising machine to any door.

In using such clamping arrangement, I propose to mount the machine at the free vertical edge of the door with the vibrating belt or its equivalent extending, that is, having its operating position, substantially in the plane of the door and disposed outwardly from such edge. In this way, when the user throws his weight away from the machine to increase the exercising effect, the reactive support will be adequate in all cases, and further, the major part of the vibration reactions will be yieldingly absorbed by the door, which is relatively heavy, and finally by the door frame through the hinges. This support also enables the machine to be used in many positions in a room, where the door swings inwardly as usual, and permits the machine to be swung out of the way tempo-

rarily when the user does not wish to wholly dismount it to put it away. There is a marked advantage in that, due to yieldingly supporting the machine, a great deal of wear is saved on the machine itself, particularly on the shaft bearings and motor armature parts, which latter are comparatively delicate and finely adjusted for greatest efficiency.

- 10 Referring in detail to the drawings, and first to Fig. 1, I show at A an ordinary door frame to which a door B is attached by the usual hinge construction C. The motor housing for the exerciser machine is indicated at 1 and, as shown, has crank arms 2 at the ends of a shaft passing transversely of the motor casing and which may be driven through a worm gear reduction, such as fully shown in my above mentioned prior application. The 15 applicator shown in Figs. 1 and 2 is a belt 3 having its ends suitably, and preferably detachably, connected to the crank arms in any suitable manner. The motor housing 1 has rigidly associated therewith a mounting device by which the housing may be securely fastened to the door at the vertical edge thereof, at any desired height from the floor. The 20 preferred arrangement of machine and mounting is shown in detail in Figs. 2 and 3. 25 In Fig. 2, the motor housing has a supporting pad or base effect at 5 machined on one vertical surface to carry a bifurcated bracket member 10. The bracket may be secured to the pad effect as by screws 11, and has arms 15 and 16 extending into embracing relation to the door stile at the free edge of the door. The arms are spaced apart sufficiently to embrace door stiles of varying 30 thickness. The door stile is indicated B'. 35 The arm 15 carries a clamping device shown as a clamping screw 17 with an enlarged swiveled clamping pad 18, there being a thumb piece 19 for turning the screw. 40 The pad and the arm 16 may have suitable friction cushioning material where these parts engage the door surface to prevent marring and slippage. Preferably, I provide a hollow shoe member 20 for the arm 16 which shoe may be molded from rubber or 45 like resilient friction material to slip over the free end of the arm. This corresponds in general to the flat taper shape of the arm 16, as shown, and may be held on by a fastening screw 21 (Fig. 2). The pad may have a similar shoe shown as a "slipover" member 22 adapted to be molded from rubber or the like. The molded rubber shoes have been found entirely suitable, in connection with the clamp above described, to hold the exerciser machine in rigid relation to the door. 50

If desired, the arm opposite the clamping screw may have a hook effect at its end, designated 25, for engaging the usual shoulder at the inner edge of the door stile, as shown in Fig. 4. The arm and the inner side

of the hook effect may be provided with a cushion member, such as 26, to prevent marring the door.

Another form of mounting is shown in Figs. 5 and 6, wherein the bracket 10' has door embracing arms, designated 30. The arms embrace the door stile as shown in the other arrangement, but in this case, each of the arms has a downwardly open slot 33 adapted to embrace the usual shaft D, to which the usual door knobs are secured. Each slot may be rearwardly recessed as at 34 to provide a crotch effect for the door knob shaft. A suitable clamping arrangement may comprise a clamping screw 35 threaded through the vertical portion 32 of the bracket and having an enlarged clamp pad 36 and thumb piece 37. In attaching the bracket to the door, the slots 33 are simply dropped over the shaft D and the clamp 40 then screwed tight.

It will be seen that with all arrangements described, the exerciser mechanism will be supported with substantial rigidity and strength and the apparatus will have the 45 various advantages heretofore mentioned.

I claim:

1. In combination, an electric motor and casing therefor, mechanism carried by the casing and adapted to impart vibrating impulses to an applicator, and a bracket rigidly associated with the casing comprising spaced arms adapted to embrace the free vertical edge of an ordinary vertically hinged door, and clamping means associated with the 100 bracket to engage the door, whereby the door will swingably support the said motor and mechanism.

2. In combination, a mechanical exerciser and vibration applicator therefor, and means to hold the exerciser on a door with the applicator extending substantially in the plane of the door, said means comprising a mounting member having spaced parts adapted to embrace the door edge between them, and clamping means carried by the mounting member to clampingly engage the door to hold the exerciser in substantially rigid relation thereto.

3. In combination, a motor and casing, means driven by the motor and carried by the casing and arranged to impart vibrating impulses to a strap, a bracket having a portion extending along one side of a door, means carried by the bracket and arranged to extend along the opposite side of such door, and clamping means carried by the bracket to hold the bracket in fixed position on the door.

4. In an attaching clamp for an exerciser machine, rigid spaced arms adapted to embrace the opposite surfaces of a door at the edge thereof, a screw clamp including a shoe on one of said arms, a yielding resilient friction member adapted to slip over the shoe to 130

engage one surface of the door, and a tubular resilient friction member adapted to slip over the arm opposite the shoe to engage the opposite surface of the door, whereby the exerciser may be prevented from movement with relation to the door solely by the friction of said yielding members in association with the clamping action of the screw.

5. In combination a mechanical exerciser and vibration applicator therefor, and means to hold the exerciser on a vertically hinged ordinary building door with the applicator extending away from the free edge of the door and substantially in line with the door, 10 said means including a door embracing bracket having rigid spaced arms adapted to embrace the opposite surfaces of a door at the edge thereof, each of the arms having a slot therein adapted to hook over the door 15 knob shaft and a clamping screw associated with said bracket for holding the bracket at said slotted portion in embracing contact with said door knob shaft.

20 In testimony whereof, I hereunto affix my
25 signature.

JAMES D. COLE.
